COMBINED AQUARIUM AND PHONOGRAPH CABINET

Robert E. Jackson, 4008 Trinity St., Los Angeles, Calif.

Filed July 28, 1964, Ser. No. 31,043

Term of patent 14 years

(Cl. D56—4)

FIG. 1.

FIG. 2.

FIG. 3.

FIG. 4.

FIGURE 1 is a top plan view of a combined aquarium and phonograph cabinet, showing my new design;

FIGURE 2 is a front elevational view;

FIGURE 3 is a rear elevational view;

FIGURE 4 is an enlarged side elevational view thereof.

I claim:

The ornamental design for a combined aquarium and phonograph cabinet, substantially as shown.
